(57) **CLAIM**

The ornamental design for the controller for video games, as shown and described.

DESCRIPTION

FIG. 1 is a top plan view of a controller for video games. FIG. 2 is a front elevation view thereof; the rear elevation view is identical with the front elevational view.

FIG. 3 is a bottom plan view thereof.

FIG. 4 is a left side elevation view thereof.

FIG. 5 is a right side elevation view thereof.

FIG. 6 is a cross sectional view taken along line 6—6 of FIG. 1 showing the horizontal cross section of the top plan view. FIG. 7 is a referential right side view showing the controller attached to the analogue keys.

FIG. 8 is a referential view showing the controller sliding in the direction the arrow indicates; and,

FIG. 9 is a referential left side view showing two controllers with their hinges being twisted.

The broken lines are for illustrative purpose only and forms no part of the claimed design.
